UNITED STATES PATENT OFFICE.

PETER ISLES, OF SWISSVALE, PENNSYLVANIA.

FURNACE-ARCH CONSTRUCTION.

958,130.

Specification of Letters Patent. Patented May 17, 1910.

Application filed January 25, 1910. Serial No. 540,062.

To all whom it may concern:

Be it known that I, PETER ISLES, of Swiss-
vale, in the county of Allegheny and State
of Pennsylvania, have invented a new and
useful Furnace-Arch Construction, of which
the following is a full, clear, and exact de-
scription, reference being had to the accom-
panying drawings, forming part of this
specification, in which—

10 Figure 1 is a plan view, partly in section,
of one end of a regenerative furnace having
a port arch constructed and arranged in ac-
cordance with my invention. Fig. 2 is a
15 sectional side elevation of the same, on the
line II—II of Fig. 1. Fig. 3 is a sectional
end view on the line III—III of Fig. 2,
showing in elevation the gas and air ports
and the port construction forming my in-
vention.

20 This invention relates to improvements in
furnace arches and more particularly to the
port arch and the end wall construction of
regenerative heating or melting furnaces.

25 The object of the invention is to provide
a construction which will withstand the in-
tense heat of a regenerative furnace for a
longer period of time than has heretofore
been possible, and a construction in which
30 the making of repairs to the end wall con-
struction is facilitated, the life of the end
wall is lengthened and the liability of delays
in the operation of the furnace caused by
caving in of the arches is largely overcome.

35 In the drawings, 2 represents the hearth
of an open hearth furnace which is con-
nected through the port opening 3 with the
regenerator flues 4. The furnace as shown
is arranged to use natural gas which it is
40 not necessary to regenerate and the gas,
therefore, is led into the furnace through
opening 5 in the opposite side walls of the
furnace, although my invention is not lim-
ited to such use but can be used with
45 furnaces using producer gases. The furnace is
provided with the usual surrounding metal
framework or shell, which, not forming
part of my invention, need not be further
described, other than that it is one of sev-
50 eral well-known constructions of such sur-
rounding framework employed with such
furnaces.

55 Another object of the invention is to pro-
vide a novel end wall construction through
which the gas and air ports extend into the
furnace, in the use of which damage to the
end wall caused by the intense heat and by

splashing of the bath in the furnace, is re-
duced to a minimum and the life of the end
wall of the furnace and of the furnace lining
is very largely increased. 60

As is shown in Figs. 1, 2 and 3, the roof
of the furnace is arched transversely and
also curves downwardly from the center of
its length toward its ends, the arched roof
over the port 3 being at the lowest point of 65
the furnace roof. The roof over the re-
generator flues 4 is also arched and is in-
clined downwardly and inwardly toward the
furnace.

Instead of keeping the roof 6 of the re-
generator flues entirely independent of the
furnace roof, as has been done heretofore,
this roof is built into and its end thrust is
resisted by the brick work in the roof or
covering 7 over the inlet ports 3. The longi-
tudinal thrust of the roof 8 over the furnace
proper in the opposite direction is also re-
sisted by the brick work of the roof 7, the
thrust of the flue roof 6 largely balancing
that of the furnace roof 7. It will be noted 75
that the joints between the brick work in the
roof 7 and also in the roof 8 extend ver-
tically.

The furnace roof 8 is arched transversely
and the thrust of the arched roof is taken 85
by the skew-backs 9 through which the
thrust is transmitted to the metal shell of
the furnace, this construction being clearly
shown in Fig. 3.

Heretofore in the construction of the end 90
walls of furnaces which divide regenerator
flues from the furnace chamber and through
which wall the gas and air inlet ports ex-
tend, the arch or roof over the ports has
been built so as to spring from a skew-back 95
located at the end of the arch, the vertical
face of the skew-back forming the end sur-
face of the port openings. In the operation
of such furnaces, the intense heat and, in
open hearth furnaces the splashing of the 100
fluid bath on the end walls has been very
destructive to these walls, burning away the
walls between the skew-back and the inter-
section of the side walls with the end wall
of the furnace in which the arch is built. 105
When the brick work in this end wall is
destroyed in this manner, the thrust of the
arch tends to destroy the arch and caving in
of these arches frequently necessitates the
shutting down of the furnace for repairs. 110

In my improved construction, the thrust
of the arch is extended or carried to a point

on the end wall where the metal shell and the side wall of the furnace take the thrust of the arch, instead of being transmitted through the dividing wall of refractory material in which the ports are located. In this way the wall can be very largely destroyed without the arch necessarily being greatly weakened, and, it not being necessary to resist the thrust of the arch as heretofore, this 5 arch and end wall can be easily and quickly repaired by applying new plastic refractory material which is dried in place thereon to the worn or burned-away portions of the end walls.

10 15 It will be seen by reference to Figs. 2 and 3 that the joints between the bricks in the port arch extend radially and as the joints approach the sides of the furnace, extend radially, the radial joints in the end wall 15 20 radiating from the center from which the curve of the arch is struck for an increasingly greater distance downwardly and outwardly into the end wall of the furnace, this construction also facilitating the making 25 of repairs and increasing the life of the arch and end wall.

In the operation of the furnaces, the air enters the furnace from the flues 4 through the port 3 and the gas is introduced through 30 the openings 5 in the side walls at the end of the furnace, shown dotted in Fig. 2. The partition 3^a in the middle of the length of the port opening deflects the incoming gas and directs it through the port opening 3 35 where it is mixed with the incoming heated air and burns. The products of combustion or burned gases pass out through a similar port opening 3 and flues 4 on the opposite end of the furnace, the gases being caused 40 to pass alternately in opposite directions across the length of the furnace from opposite ends of the furnace in the usual manner.

Modifications in the construction and arrangement of the parts may be made without departing from my invention.

I claim:

1. In a regenerative furnace, a furnace end wall having inlet and outlet ports therein connecting the furnace and the regenerators, 50 and an arched roof over said ports, the radial joints in said arch radiating from the

center of the arch and extending to the side walls of the furnace; substantially as described.

2. In a regenerative furnace, a furnace end 55 wall having inlet and outlet ports therein connecting the furnace and the furnace flues, and an arched wall over said ports, the radial joints in said arch radiating and extending beyond and below the curved roof 60 surface defining the top of the inlet port opening; substantially as described.

3. In a regenerative furnace, a furnace end wall having inlet ports thereto, an arched roof over said inlet ports, the radial joints 65 in said arch radiating from the center of the arch and extending beyond the inner surface of the side walls of said furnace and extending below the spring of the arch, a downwardly and inwardly inclined arched 70 roof over the furnace flues engaging with said port roof and a downwardly and outwardly inclined furnace roof engaging with the opposite side of said port roof; substantially as described.

4. In a regenerative furnace, a furnace end wall having inlet ports thereto, an arched roof over said inlet ports, the radial joints in said arch extending at least to the inner surface of the side walls of said furnace 80 and extending below the spring of the arch and radiating from the center of the spring of the arch, a downwardly and inwardly inclined arched roof over the furnace flues engaging with said port roof and a downwardly and outwardly inclined furnace roof 85 engaging with the opposite side of said port roof; substantially as described.

5. In a regenerative furnace, a furnace end wall having inlet ports thereto, an arched roof over said inlet ports, said arch extending beyond the inner surface of the side walls of said furnace, the joints in said end wall extending radially from the center of the spring of said arch; substantially as described.

In testimony whereof, I have hereunto set my hand.

PETER ISLES.
